CLAIM

The ornamental design for an aerosol overcap, as shown and described.

DESCRIPTION

FIG. 1 is a front perspective view from above and to one side of an aerosol overcap showing my new design.

FIG. 2 is a front elevational view of the aerosol overcap of FIG. 1.

FIG. 3 is a left side elevational view of the aerosol overcap of FIG. 1, the other side being a mirror image thereof.

FIG. 4 is a top plan view of the aerosol overcap of FIG. 1; and,

FIG. 5 is a back elevational view of the aerosol overcap of FIG. 1.

The bottom of the aerosol overcap forms no part of the claimed design.
